CLAIM

The ornamental design for a multi-mode electronic device with display screen, as shown and described.

DESCRIPTION

FIG. 1 is a front view of a multi-mode electronic device with display screen showing our new design;

FIG. 2 is a back view thereof;

FIG. 3 is a left side view thereof;

FIG. 4 is a partially enlarged view thereof as indicated in FIG. 3;

FIG. 5 is a right side view thereof;

FIG. 6 is a top view thereof;

FIG. 7 is a bottom view thereof;

FIG. 8 is a perspective view thereof;

FIG. 9 is a perspective view thereof shown in first open position;

FIG. 10 is a perspective view thereof shown in second open position;

FIG. 11 is a perspective view thereof shown in third open position;

FIG. 12 is a partially enlarged view thereof as indicated in FIG. 11;

FIG. 13 is a perspective view thereof shown in fourth open position; and,

FIG. 14 is a perspective view thereof shown in an open position, the unclaimed views are identical to those shown in FIGS. 1-13, the only difference being the number of gears. The features shown in broken lines in the drawings depict environmental subject matter and form no part of the claimed design.
